BAG CLOSURE MEANS

George C. Nydegger, Alameda, Calif.

Application July 13, 1936, Serial No. 90,291

8 Claims. (CL 229—62)

The invention relates to closure means particularly adapted for closing the open ends of bags, or the like.

An object of the invention is to provide a closure means of the character described which may be easily and readily applied to a bag for closing the open end thereof and with substantially equal ease removed for opening the bag and when once removed may be re-used as often as desired to close the bag with its partially filled contents.

Another object of the invention is to provide a closure means of the character above which will not require the use of glue, staples or other conventional fastening means and will not require the fastened attachment of any portion of the means to the bag but, on the contrary, will be completely removable therefrom and the locking means exclusively carried by the closure.

A further object of the invention is to provide a closure of the above character which, in addition to its function of closing and re-enforcing the open end of the bag or the like, will afford an attractive display for printed matter and will be so arranged as to permit mounting of part thereof at the inner side of the bag where the wall of the bag is formed of transparent material so as to avoid the necessity of printing directly upon such material.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is an elevational view of a closure means constructed in accordance with the present invention.

Figures 2, 3, and 4, are perspective views showing the closure steps in the application of the closure to a bag.

Figure 5 is a rear view of the closure in attached position.

Figure 6 is a sectional view taken substantially on the plane of line 6—6 of Figure 5, with the thickness of the several parts increased in view of clarity.

Figure 7 is an elevational view of a modified form of the closure.

Figures 8 and 9 are perspective views of the

steps employed in attaching the form of the closure illustrated in Figure 7 to the bag.

Figure 10 is a sectional view taken substantially on the plane of line 10—10 of Figure 9, and shown with the thickness of the several parts increased in view of clarity.

The closure means illustrated in the accompanying drawing comprises a blank 12, preferably of cardboard or other stiffened paper or metal or the like, and which is adapted for positioning over the upper open end 13, of a bag, 14, for closing the bag. As will be more clearly understood hereafter, the blank is formed for folding together with the open end of the bag so as to provide a series of interlocking folds 15 which prevents the removal of the closure from the bag and also the unfolding of the closure itself. To this end, the blank is formed with a plurality of scored lines 16, 17 and 18 which divide the blank into a plurality of adjacent transversely extending strips or areas 19, 21, 22 and 23, which on folding of the blank at the scored lines provide the interlocking folds above referred to. In attaching the closure to a bag the upper end 13 of the bag is placed opposite the line 16 and the blank folded along this line to confine the upper end of the bag between the strips 19 and 21, as illustrated in Figure 2. With the upper end of the bag so confined the blank is again folded along the line 17, whereby the strip 19 is turned down against the side 24 of the bag and the engaged portions 19 and 21 of the blank and the upper end 13 of the bag disposed opposite the portion 22 of the blank. As will be understood, and as readily seen from Figure 6, this latter fold inter-seams the upper end of the bag with the portions 19, 21 and 22 of the blank and thereby not only locks the blank against removal from the bag, but also positively seals off and closes the upper end of the bag. To hold the bag 40 and closure in the last mentioned folded position there is provided at the opposite ends of the strip 22 a pair of tabs 26 which extend transversely from the strip 22 and are adapted for bending around the ends of the folded formation of the 45 blank and bag for extension into the space between the strips 19 and 21 to securely lock the blank against unfolding. To facilitate the insertion of the tabs into this space the ends 27, of the strip 21 may be cut away to define receiving portions for the tabs. Also, if desired, the tabs may be provided with nibs 28 which cooperate with cut out portions 29 adjacent the ends of the strip 19 for normally holding the tabs 50 against withdrawal. The character of the nibs 55

and cut out portions may be varied to afford a releasable attachment or a positive lock as desired.

With the closure thus applied to a bag, the extremity 23 of the blank is caused to overlie the front side 31 of the bag and may be bent at the line 18 to assume a position inclined to the normal vertical position of the folded portions. I also prefer to form in the section 19 a segment 32, which is severed from the section and extended to the line 16 to enable the bending of this segment on the line 16 independent of the section 19. Thus, on folding of the several portions as aforesaid, the segment 32 will remain out 18 of the folds and normally lie against the rear side 24 of the bag in a manner similar to the positioning of the section 23 at the front side of the bag. These two depending portions 23 and 32 provide an important function of holding the 20 folded portion of the blank erect to properly display printed matter which may be impressed thereon and also provide an appreciable area for the receipt of printed matter on their own surfaces. If desired the scored lines 16 and 18 may 25 be omitted to increase the rigidity of the vertical support for the folded portions provided by the sections 23 and 32. These depending members also assist in re-enforcing the top of the bag adjacent the folds. Where, as in some instances, 30 it is desirable to bend the folded portions of the closure down flat against the top of the bag to facilitate packing and where further the use of the printed matter on the depending portions 23 and 32 is not required, these two portions may 35 be dispensed with without affecting the character of the interlocked closure of the portions 19, 21 and 22. In such instances, the segment 32 may be left integrally with the portion 19 and the blank terminated at the line 18 with portion 40 23 deleted.

A modified form of the invention has been illustrated in Figures 7 to 10 of the drawing in which the closure has been particularly designed for use with bags of transparent material, or 45 having a window of transparent material. The blank 12' of this embodiment is formed with a series of scored lines 33, 34, 36 and 37 and defined between these lines are a plurality of strips or areas 38, 39, 41, 42 and 43, which are adapted 50 in a manner similar to that illustrated in the first embodiment to interfold with the upper end of the bag. In applying the blank to the bag, the blank is folded along the line 36 to position the areas 38, 39 and 41 opposite to the areas 42 and 43, and the areas 42 and 43 are placed within 55 the upper end of the bag while the areas 38, 39 and 41 are placed against the outer side of the bag, as illustrated in Figure 8. The blank is next folded along the lines 34 and 37, as illustrated in Figure 9, to crimp the upper end of the bag within the folded blank portions as further 60 illustrated in Figure 10. To hold the blank in this latter folded position, a pair of tabs 26' are formed at the ends of the strip 39 and are bent 65 around the ends of the folded portion and inserted into the space between the areas 41 and 42, as shown in Figure 10, to lock the several portions against unfolding. As will be understood, the strip 43 is placed at the inner side 70 of the transparent portion of the bag whereby any printed matter placed thereon may be read and advantage is further taken of the gloss imparted to such printed matter by the usual character of the transparent material to increase the general attractiveness of the assembly. Also, as

will be clear from Figure 10, the blank portion 38 is arranged to lie against the rear side of the bag and co-operates with the blank portion 43 to hold the folded areas of the blank erect as in the first embodiment.

It will now be understood that the closure means of the present invention may be simply and readily attached to the open end of a bag, for not only closing the bag, but also re-enforcing the upper end thereof, and when so attached will provide an attractive display for printed matter which would otherwise need be placed on the bag itself. It will further be understood that the closure may be readily removed from the bag to permit its opening simply by withdrawing the tabs 26 and after the desired contents of the bag have been removed, the closure may be again applied thereto and in this manner re-used for a substantially unlimited period.

I claim:

1. A closure means of the character described comprising, a blank of material having adjacent portions foldable one over another to interlock therebetween the open end of the bag or the like, means for holding said portions in folded position, one of said portions having a part severed therefrom and adapted to extend over a side of said bag upon folding of said portions.

2. A closure means for a bag, or the like, comprising, a blank of material having an end 30 adapted for positioning within the open end of said bag, portions adjacent said blank end being adapted for folding one over the other to lock therebetween the open end of said bag, and means for holding said portions in folded 35 position against removal from said bag comprising, tabs extending transversely from one of said portions forming an outer side of said blank in folded position and bendable around the ends of the folded portions to an opposite side thereof, and interlocking cut-out and projections portions 40 on said last named side and said tabs.

3. A closure means for a bag or the like, comprising, a blank of material adapted for folding to dispose the free ends thereof respectively 45 within and without the open end of the bag, the intermediate portion of said blank having adjacent portions adapted for folding one over the other and together with the open bag end to interlock said end within the folds of said portions, tabs extendible from the ends of one of 50 said portions forming an outer side of the blank in folded position and bendable around the ends of said folds to an opposite side thereof, and interlocking cut-out and projection portions on said 55 last named side and said tabs.

4. A closure means for a bag comprising, a separate member adapted for placing against the open end of a bag and along the side walls thereof and having a plurality of adjacent portions foldable with the bag side walls into a plurality of folds locking the side walls and said member together, and tabs of relatively stiff material extending transversely from the opposite ends of one of said member portions forming an outer 60 side of said folds and bendable around the ends of said folds to an opposite side thereof to hold the same from unfolding, said member having cut-away portions at opposite edges of said last-named side for receiving said tabs into the interior of the fold formed by said side to hold the tabs therein from unfolding.

5. A closure means for a bag comprising, a separate member adapted for placing against the open end of a bag and along the side walls there- 75

5 of and having a plurality of adjacent portions foldable with the bag side walls into a plurality of folds locking the side walls and said member together, and tabs of relatively stiff material extending transversely from the opposite sides of said member at one side of said folds and, bendable around the ends of said folds, said member being formed with cut-away portions at opposite edges of an opposite side of said folds for receiving said tabs into the interior of one of said folds to hold the same from unfolding.

10 6. A closure means for a bag comprising, a separate member adapted for placing against the open end of a bag and along the side walls thereof and having a plurality of adjacent portions foldable with the bag side walls into a plurality of folds locking the side walls and said member together, tabs extended transversely from one of said member portions forming an outer side of said member in folded position and bendable around the ends of said folds to an opposite side thereof, cut-out portions in said member on said last named side, and hooked portions on said tabs for locking the same in said cut-out portions.

15 7. A closure means for a bag comprising, a separate member adapted for placing against the

open end of a bag and along the side walls thereof and having a plurality of adjacent portions foldable with the bag side walls into a plurality of folds locking the side walls and said member together, tabs extended transversely from one of said member portions forming an outer side of said member in folded position and bendable around the ends of said folds to an opposite side thereof, and interlocking cut-out and projection portions on said last named side and said tabs. 10

15 8. A closure means for a bag comprising, a separate member adapted for placing against the open end of a bag and along the side walls thereof and having a plurality of adjacent portions foldable with the bag side walls into a plurality of folds locking the side walls and said member together, tabs extended transversely from one of said member portions forming an outer side of said member in folded position and bendable around the ends of said folds and into the interior 20 of one of said folds, said member being provided with cut-out portions at said last named fold spaced from the ends of said folds, and projections on said tabs for locking in said cut-out portions. 25
